UNITED STATES PATENT OFFICE.

WALTER R. NOE, OF NEW YORK, N. Y.

PENCIL.

Application filed June 18, 1921. Serial No. 473,623.

My invention relates to mechanical pencils of the type in which the lead is advanced by means of a push rod, operated through screw threads by the turning of the 5 cap. It has for its object the provision of a construction in which the parts may be disconnected to allow refilling, with the least motion and a minimum of effort. The invention will be fully described hereinafter 10 and the features of novelty will be pointed out in the appended claims.

In the accompanying drawings which are on an enlarged scale and show an example of my invention without defining its limits, 15 Figure 1 is a longitudinal section showing the relative position of the parts when the lead first shows at the writing point; Fig. 2 is a longitudinal section partly in elevation, in a plane at right angles to Fig. 1, 20 and showing the relative position of the parts when the lead has been completely advanced; Fig. 3 is a detail view, partly in section, of the interior and removable parts of the pencil; Fig. 4 is an end view 25 of Fig. 3; Fig. 5 is a cross section on the line 5—5 of Fig. 1; and Fig. 6 is a detail view of the cap.

As shown in the drawings the pencil comprises a tubular barrel 10 of suitable material and formed with a tapering end 11, 30 said barrel itself preferably having a uniformly smooth exterior surface. In the construction shown in the illustration a tube 12 extends into the barrel 10 and lengthwise thereof, the exit end 12^A of said tube being located exteriorly of and fitting against the apex of the tapering end 11 of 35 said barrel and forming the actual exit for the lead 13. The entrance or inner end of the tube 12 is fitted into a plug 14 fixed 40 within the barrel 10 and having an axial bore in registry with the tube 12 and forming therewith a continuous passage for the lead 13; in the preferred arrangement the 45 axial bore of the plug 14 at its entrance end is cone shaped as shown at 15. The plug 14 fits tightly in the barrel 10 and is securely fastened by friction or otherwise. The 50 parts so far described may be of any suitable construction and form no part of the invention.

The inside of the barrel from the cone 15 to the top end is perfectly smooth, and accommodates a removable sleeve 16 which 55 fits snugly in said barrel 10. This sleeve is internally screw threaded throughout its

entire length as indicated at 17 and is formed with an annular shoulder 18 arranged to fit against the end of the barrel and thus limit the movement of said sleeve 60 16 into the barrel 10. Friction may be depended upon to prevent the turning of this sleeve in the barrel or a lug 19 may be added to the shoulder 18, said lug fitting into a notch formed in the end of the barrel as 65 shown in Fig. 6.

As may be seen in the illustration the usual push rod 20 is attached at its upper end to a follower 21 which is in screw-threaded engagement with the screw threads 70 17 of the sleeve 16 and is fitted to slide between two parallel tubular guides 22 and 23 extending lengthwise of the pencil. The inner sides of these tubes are bent in or away from each other for their entire length 75 as shown at 24 and 24^A in Fig. 5, and the follower 21 is correspondingly shaped to fit the space between these tubes so as to slide lengthwise thereof and being held against independent rotation thereby. The 80 tubes are closed at their lower ends by an apertured cap 25 which is concave on the side opposite that which is joined to the tubes and which forms the exit for the push rod as well as the holder for the active lead 85 in refilling.

At their upper ends the tubes 22 and 23 terminate in the form of a cylindrical end member 26 externally screw threaded for a short distance as indicated at 27 and apertured in registry with the tubes as shown at 28 and 29 to leave an open end lead chamber in each of the tubes adapted to be closed by means of a cap 30 which screws upon the threads 27 of the end member 26. 95

When the pencil is operative or in other words when it is loaded and the lead begins to show itself at the exit end, the follower 21 occupies a position part way down the sleeve 16 for instance as shown in Fig. 1. 100 As the cap 30 is rotated and carries with it the end member 26 and tubes 22 and 23, the follower 21 will be caused to partake of this rotative movement and, because of its screw-threaded connection with the internal thread 105 17 of the sleeve 16, will be forced to slide longitudinally between the tube 22 and 23 toward the end of the pencil and carry the push rod with it. This lengthwise movement of the latter forces the lead through 110 the exit 12^A. When the lead has been entirely used, that is when the pencil requires

refilling, the follower 21 has worked through the entire length of the sleeve 16 and out of engagement with the screw threads 17 thereof, as shown in Fig. 2, so that, as rotation of the cap continues, said follower will revolve in the open space beyond said sleeve and within the barrel without further longitudinal progress.

To refill the pencil, the cap 30 is pulled away from the barrel in an axial direction and carries with it the sleeve 16, lead chamber tubes 22 and 23, follower 21, and push rod 20, until all have been removed from the barrel. The cap 30 may then be unscrewed to obtain a new lead from one of the lead chambers and, before the cap 30 is replaced, the sleeve 16 is removed by sliding it in an axial direction over the end member 26 and is replaced in position by sliding it back onto the tubes 22 and 23 at the other end. As this is done the sleeve 16 will engage the follower 21 and shift it from the position shown in Fig. 2 to the position shown in Fig. 3. The cap is then replaced upon the threads 27 or it may have been so replaced immediately after the sleeve 16 was removed and while the parts were thus separated. The new lead is inserted into the bore 28^A until it meets the push rod. The sleeve is then slidably inserted into position in the barrel 10 and the cap is turned until the follower 21, which will engage the thread 17 in the sleeve 16 has advanced sufficiently to cause the lead to project at the exit 12^A.

The construction is an improvement on the usual pencil of this type in that it allows refilling without the tedious unscrewing process usually necessary to bring the follower 21 or its equivalent back the entire length of the barrel from the dead position when the lead has been completely used. It also relieves the tendency to break the mechanism by forcing. In the ordinary mechanical pencil, of which the present construction is an improvement, when the follower 21 or its equivalent has traveled the desired distance toward the exit 12^A, the parts become tight and further turning of the cap will break or injure the parts and destroy the pencil. In my improved pencil the cap may be turned indefinitely without injuring any part. The necessity for refilling of course is made evident by the fact that the fractional piece of lead remaining at the exit end 12^A refuses to be advanced further.

Various changes in the specific form shown and described may be made within the scope of the claims without departing from the spirit of my invention.

I claim:

1. A mechanical pencil comprising a barrel having an exit end, an internally screw-threaded sleeve fitted within said barrel and terminating at an intermediate point therein, guide members extending lengthwise of said sleeve, lead propelling means in screw-threaded engagement with said screw-threaded sleeve and means whereby relative rotation between said sleeve and said guide members with the lead propelling means thereon is brought about at will, to shift said lead propelling means lengthwise of said guide members and barrel to an inoperative position beyond the inner end of said sleeve, the latter and said guide members being removable as a unit from said barrel to permit replenishment of the lead, and said guide members being independently removable from said sleeve to permit resetting of the lead propelling means at the starting point without requiring a reverse rotation of said sleeve.

2. In a mechanical pencil an internally screwthreaded sleeve within a barrel and slidably removable therefrom, a shoulder mounted on said sleeve and limiting its movement into said barrel, said sleeve terminating at an intermediate point in said barrel to provide a free space within said barrel beyond the operative range of said sleeve, guide members within said sleeve, a cap removably attached to said guide members independently of the sleeve and forming the top of the pencil, said guide members being slidably removable from said sleeve in either direction when the cap is detached and in one direction when the cap is in place, said guide members carrying a propelling unit in screw threaded engagement with said sleeve and having an operative range beyond the operative range thereof, and a push rod attached to said unit and capable of advancing a lead until said unit has worked out of engagement and into said opening beyond said sleeve.

Signed at New York in the county of New York and State of New York this 16th day of June A. D. 1921.

WALTER R. NOE.
